RETICULE FOR FIREARM TELESCOPES

Theodore W. Stein, Butte, Mont.

Application July 16, 1948, Serial No. 39,070

3 Claims. (Cl. 33—50)

1

This invention relates to improvements in objective lens reticles for telescopes, and more particularly to an improved reticle having a minute sphere or dot at the intersection of its cross hairs for use in a sighting telescope for a firearm, such as a rifle.

It is among the objects of the invention to provide an improved sighting reticle for a rifle sighting telescope which reticle includes a pair of fine cross hairs and a minute sphere secured to the cross hairs at their intersection or cross-over point, and wherein the sphere or dot is so positioned relative to the cross hairs that it is not distorted by capillary attraction of its material along the cross hairs during application or formation thereof, receives full lighting from the objective lens of the telescope so that its outline is always sharp and clear, and places the cross hairs slightly out of the focal plane of the telescope so that the cross hairs do not reflect the light and thus cause distortion of the image of the target or the sphere.

Other objects and advantages will become apparent from a consideration of the following description and the appended claims in conjunction with the accompanying drawing, wherein:

Figure 1 is a longitudinal side elevation of a rifle sighting telescope having a portion broken away and shown in cross-section to illustrate the application of a sighting reticle thereto;

Figure 2 is a front elevation on an exaggerated scale of a rifle sighting telescope reticle illustrative of the invention;

Figure 3 is a rear elevation of the reticle illustrated in Figure 2;

Figure 4 is a transverse cross-section taken substantially on the line 4—4 of Figure 2; and

Figure 5 is an elevation on a still further exaggerated scale of a fragmentary portion of the reticle showing the application of the minute sphere or dot to the cross hairs of the reticle.

With continued reference to the drawing, the telescope, generally indicated at 10, has a barrel 11 mounted in a holder 12 secured to the rifle barrel 13, and has at one end the conventional eye-piece and at its opposite or front end a conventional objective lens, not illustrated. A sighting reticle, generally indicated at 14, is mounted in the barrel 11 between the objective lens and the eye-piece and is supported in operative position substantially perpendicular to the longitudinal center-line of the barrel by an inner sleeve 15, having an annular groove therein receiving the annular frame of the reticle.

The reticle 14 has a circular frame ring 16

55 passes through the center of the sphere, the cross

2

and two fine cross hairs 17 and 18 extending diametrically across the ring substantially perpendicular to each other and crossing over each other at a cross-over point which is preferably located at the exact center of the ring 16. The two cross hairs 17 and 18 are of microscopically small diameter and are conventionally formed of pieces of spider web strand or of threads of platinum wire or a synthetic plastic, such as "nylon," and are disposed in a substantially common plane within the ring 16.

In order to improve the accuracy of the sighting telescope and the visibility of the point of intersection of the cross hairs 17 and 18, a minute sphere 19 is secured to the cross hairs at their point of intersection. The construction so far described is known to the art and the sphere applied at the point of intersection of the cross hairs is commonly referred to as a "dot."

20 The sphere or dot 19 is made of some suitable material rendered plastic by a volatile solvent and is intended to harden in true spherical shape when the solvent evaporates. It has been found, however, in this prior practice, that in applying 25 the material to the cross hairs, capillary attraction of the material along the cross hairs tends to seriously distort the dot from its spherical shape. Also, when the dot is applied so that the cross hairs extend through the center thereof, as 30 is conventional, and the dot disposed so that the focal plane of the telescope also extends through its center, it does not receive full lighting from the objective lens of the telescope and hence, does not have a sharp and definite outline. Also 35 the cross hairs, being also disposed in the focal plane of the telescope, refract the light to some extent and distort the image of the target as seen through the telescope.

In order to overcome these difficulties, the 40 present invention applies the dot or minute sphere 19 to the cross hairs 17 and 18 so that the sphere is disposed at one side of the common plane in which the cross hairs 17 and 18 are substantially included, as is clearly illustrated 45 in Figures 4 and 5. With this construction the sphere contacts the cross hairs only within a very restricted area of its surface and the capillary attraction of the cross hairs for the material of the sphere does not cause an equatorial distortion of the sphere, as is the case when the cross hairs extend through the center of the sphere, as indicated by broken lines in Figure 5. With 50 this arrangement, when the reticle is properly mounted so that the focal plane of the telescope passes through the center of the sphere, the cross

hairs 17 and 18 are slightly displaced from the focal plane with the advantages above enumerated.

While it is theoretically preferable to have the sphere or dot entirely at one side of the common plane of the cross hairs, this is not quite possible in practice, since a sufficient part of the sphere must surround the cross hairs to securely fasten the sphere to the cross hairs at their point of cross-over and in practice the sphere is disposed with a very large percentage or substantially all of its volume at one side of the common plane of the cross hairs.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. In a telescope reticule having a pair of cross hairs disposed substantially perpendicular to each other, substantially in a common plane and crossing over each other adjacent their mid-length locations, and a minute sphere secured to said cross hairs at their cross over point, the improvement which comprises having said sphere secured to said cross hairs so that substantially all of its volume is one side of said common plane.

2. In a reticule for a rifle sighting telescope which reticule includes a pair of cross hairs disposed substantially in a common plane and crossing over each other at a point intermediate their ends, and a minute sphere secured to said cross hairs at their cross over point, the improvement which comprises having said sphere secured to said cross hairs so that said sphere is disposed to one side of said common plane and contacts said cross hairs only within a restricted area of its surface.

3. A reticule for a rifle sighting telescope comprising a pair of cross hairs disposed substantially perpendicular to each other in a common plane and crossing over each other substantially at their mid-length locations, and a minute sphere attached to said cross hairs at their cross over point with its center spaced from said common plane.
